DEFECTIVE MOUNT DETECTING AND
SEGREGATING DEVICE

John F. Donovan, East Cleveland, and John Flaws, Jr., Cleveland Heights, Ohio, assignors to General Electric Company, a corporation of New York

Application June 30, 1934, Serial No. 733,158

11 Claims. (Cl. 209—80)

Our invention relates to devices used in the manufacture of incandescent lamps and similar devices which comprise a filament for automatically detecting and segregating defective filament mounts. The device is particularly suited for use on automatic lamp making machines, since it prevents a defective mount from completing the full course of lamp manufacturing operations before being discarded. An object of our invention therefore is to provide a device for detecting the presence of a defective mount. Among the defects detected are: the absence of a filament, an improperly mounted filament, the absence of one or more support or leading-in wires, and the presence of bent or distorted support or leading-in wires. A feature of our invention is the provision of means for automatically removing a mount from a lamp making machine to prevent further operations thereon. Further features and advantages of our invention will appear from the following description of species thereof and from the drawings.

In the drawings, Fig. 1 is a plan view of a device comprising our invention; Fig. 2 is a side elevation thereof; Fig. 3 is a perspective view of feeler mechanism; and Fig. 4 is a wiring diagram of an electrical controlling circuit therefor.

The particular device shown in the drawings was designed for use with filament mounting machines of the type disclosed in Patent 1,907,532, Flaws, issued May 9, 1933, and is preferably supported on and operated from said machine. The lamp mount 10 (Fig. 1) to be inspected is carried by a head 11 of the mounting machine which remains in the position shown during a cycle of operation of the inspection device. The said mount is located directly above the feeler mechanism shown in Fig. 3 with the stem tube 12 disposed between the fingers of a holder 13 and the flare portion 14 immediately above said holder. The feeler mechanism illustrated consists of three feelers 15, 16 and 17 which are mounted on hubs 18, 19 and 20 respectively. The said feelers engage the filament 21 of the mount when they are moved upward. The said hubs 18, 19 and 20 are mounted on a pin 22 in a bracket 23. Said bracket 23 is clamped to a rod 24 and is moved vertically upward by said rod. As the upward movement occurs, the bifurcate end portions 25 and 26 of each feeler strike the filament 21 on either side of each of the three support wires 27 with a force equivalent to the effective weight of the weights 28 on the legs 29 of the feelers. After the feelers come in contact with the filament, as shown, the additional movement of bracket 23 causes the hubs 18, 19 and 20 to turn, thereby swinging the legs 29 of the feelers outward. The force with which the feelers strike the filament is sufficient to loosen said filament from a support wire if said wire has become wedged between turns of the filament. Should one or more of the support wires be missing, bent out of place or not bent completely around the filament, the feelers adjacent thereto will not be swung or rotated, but will instead be carried upward, and the leg 29 thereof will hang vertically as shown. A missing filament 21, or leading-in wire 30 or 31, as well as a filament not clamped to the leading-in wires will also result in the failure of a feeler to be rotated. Stop pin 32 in bracket 23 prevents counterclockwise rotation of the feeler legs and determines the rest position thereof.

The defective mounts are removed by the holder 13 from the mounting machine head 11 which is opened by mechanism controlled by the position of the feelers. Both operations are electrically controlled by a circuit operated by the switching mechanism shown in Fig. 3. The said switching mechanism consists of a pair of contact arms 33 and 34 which carry contacts 35 and 36 respectively, and is brought into operative relation to the feeler mechanism after the feeling operation has been performed by an upward movement of rod 49 into the position shown. Contact arm 33 is mounted on a lever 37 which is supported on a pin 38 on a bracket 39 which is mounted on the rod 49. Said arm 33 is kept from making contact with the other arm 34 by a spring 40 which is located between a post 41 in the lever and a post 42 in bracket 39. Contact arm 34 is mounted on an insulating block 43 in bracket 39. The upward movement of the mechanism is not completed until contact arm 33 is brought against the end of a vertically hanging feeler leg 29 should one or more be hanging in this position. If the mount is defective and one of the legs is hanging vertically, contact arm 33 will be pressed down so the contacts 35 and 36 will touch each other and the latch 44 will slip over pin 45 in lever 37, holding the contacts together. The said latch 44 is turned about pin 46 in bracket 39 by a spring 47 extending between a post in the latch and a post in the bracket. The feeler mechanism is insulated from the rest of the machine by insulating bushing 48. Both the feeler mechanism and the switch mechanism are supported through

their operating rods 24 and 49 respectively which are reciprocated vertically in standard 50 (Fig. 2) by cam operated mechanism (not shown) associated with the mounting machine.

5 As shown by the wiring diagram in Fig. 4, the feeler switch serves indirectly to ground circuits through solenoids 51 and 52 which are connected to one lead of the secondary of transformer 53. The other secondary lead from the transformer 10 is grounded to the mounting machine and the primary of said transformer is connected to a source of electricity. The solenoid 51 causes the mounting machine head 11 to open and release the mount into holder 13 so that it may be removed thereby. As shown in Fig. 1, solenoid 51 is coupled to rod 54 by link 55, and when operated, causes rod 54 to shift so that pin 56 in lever 57 shifts to pocket 58 in said rod. This motion is produced against the pull of spring 59 which 15 extends between a post in the rod and another post in a stationary part of the machine. Normally the said spring 59 holds the rod 54 in such a position that pin 56 is in groove 58' in the rod and is therefore not affected by the longitudinal 20 movement. On the other hand when said pin 56 is in the pocket 58, a longitudinal movement of rod 54 causes the pin to be moved. Movement of pin 56 turns lever 57 about pin 60, causing pin 61 in the lever to strike the release arm 25 62 of the mounting machine head. When arm 62 turns the jaws of the head 11 open and release the mount into holder 13. Solenoid 52 operates mechanism which causes the holder 13 to be removed or indexed away to allow an empty 30 holder to be brought into position when the next mounting machine head is presented before the inspection device.

The holder 13 receiving the defective mount is one of a plurality of holders fastened at intervals 40 to an endless chain 63 which is supported at this location by sprocket 64. The sprocket 64 is mounted on a shaft 65 which is mounted on a bracket 69 and supports pairs of jaws 66, 67 which ensure the removal of broken stem arbors 45 68 as hereinafter explained. The said bracket 69 is slidably mounted on rods 70 and 71 extending from standard 50, and is moved back and forth thereon to place the holders 13 about the lamp stem tube, by lever 72 (Fig. 2) which it 50 engages through pin 73. Lever 72 is turned by mechanism (not shown) of the mounting machine and moves the entire sprocket 64 and chain forward thereby disposing the fingers of a holder 13 around the stem tube 12 of a mount in the 55 machine head each time a head is indexed into a position before the device, and moves the chain back while the machine heads are indexing.

If the mount being inspected is defective, solenoid 52 will have turned rod 74 about pin 75, so 60 that pin 76 in lever 77 will be located in the pocket 78 in said rod and latch 79 will have caught pin 80 in the rod, holding it in this position. The solenoid moves rod 74 against the pull of spring 80' which is located between standard 50 and 65 said rod 74. The latch 79 is mounted on pin 81 in standard 50 and is pulled by spring 82 which is located between pins in the latch and in the standard. If the mount is not found defective, pin 76 will lie in the slot 84 in rod 74 and, since 70 lever 77 is mounted on shaft 65, will not be affected by the back and forth movement thereof. When the pin 76 is in pocket 78, the movement of bracket 69 turns lever 77, causing the pawl 85 carried thereby on pin 86, to turn the ratchet 75 wheel 87 and shaft 65 on which said wheel is

mounted. This motion indexes an empty holder into the operating position and pulls a contact finger 88, which permits the inspection device to operate only when the mount machine head contains a mount, away from the said head.

The contact finger 88 is connected by wire 89 to the feeler switch 33-34 and is mounted on insulating block 90 on shaft 91. During the inspection operation, the shaft 91 is turned so that the finger 88 makes contact with the mounting machine head 11 if the head contains a mount but does not contact with the head if it is empty. Whether or not the finger 88 makes contact with the head is determined by the position of the stem holding jaws therein. When the said jaws 15 contain a mount they are, of course, extended and cause the head to engage said finger 88. In the contacting position, arm 92 on shaft 91 is against a stop screw 93 in post 94 against which it is held by spring 95. The spring extends between a post in bar 96 which is attached to arm 92 and post 94. The withdrawing of the chain mechanism from the mounting machine causes the pin 97 on bracket 69 to move in the slot 98 in bar 96 until it reaches the end thereof, whereupon the said bar is actuated and pulls the contact finger 88 away from the mounting machine head 11.

The stem arbor gripping jaws 66, 67 are mounted on a turret 100 which is mounted on the shaft 30 65 below the sprocket 64. The said jaws are provided for the purpose of insuring removal of broken arbors from on top of the feelers 15, 16, 17 so said feelers may operate properly. The jaws 66, 67 are located below the mount holders 35 13 as said holders pass around the sprocket 64. The stationary jaw 66 is mounted on a post 99 in turret 100 and the movable jaw 67 is mounted on an arm 101 on post 102 in said turret. When the sprocket 64 and shaft 65 are advanced toward 40 the feeler mechanism, the jaws 66, 67 are held open by a cam 103 which is fastened to the bracket 69 and is engaged by roller 104 in arm 101. Upon rotation of the turret 100, the roller 104 passes from the cam 103, and a torsion spring 45 105, which is located about post 102 and engages turret 100 and arm 101, closes the said jaws. The jaws remain closed until the roller again engages the said cam 103, which occurs when the holder 13 below which the roller is located leaves 50 the periphery of the sprocket 64.

The feeler and its switch mechanism move down to permit indexing of the mounting machine heads 11 which take the path indicated by the dot-dash line 105'. Upon reaching the lower 55 limit of movement of said feeler mechanism, an arm (not shown) on latch 44 of the switching mechanism strikes pin 106 (Fig. 2), causing lever 37 to be released, and permitting the contacts 35 and 36 to be drawn apart. With the 60 advancing movement of the chain 63 and sprocket 64 toward the mounting machine head 11, one end of latch 79 is struck by a portion of lever 77, causing said latch to turn and be disengaged from pin 80 to release the rod 74.

What we claim as new and desire to secure by Letters Patent in the United States is:

1. In a device of the class described, a movable holder for incandescent lamp mounts comprising a filament and support wires engaging said 70 filament, an inspection device disposed adjacent the path of movement of said holder comprising a feeler, mechanism for advancing said feeler toward said mount, said feeler being adapted to engage said filament and be displaced thereby 75

when said filament is properly located on said mount, and means operated by said feeler upon failure thereof to be displaced due to an improperly mounted filament or to the absence of a filament for indicating the presence of the defective mount in said holder.

2. In a device of the class described, a movable holder for incandescent lamp mounts comprising a filament and support wires engaging said filament, an inspection device disposed adjacent the path of movement of said holder comprising a pivotally mounted feeler balanced on its pivot so as to be swung freely thereon by a comparatively slight force, mechanism for advancing said feeler toward said mount, said feeler being adapted to engage said filament and be pivoted thereby when said filament is properly located on said mount, and means operated by said feeler upon failure thereof to be displaced due to an improperly mounted filament or to the absence of a filament for indicating the presence of the defective mount in said holder.

3. In a device of the class described, a movable holder for incandescent lamp mounts comprising a filament and support wires engaging said filament, an inspection device disposed adjacent the path of movement of said holder comprising a pivotally mounted feeler balanced on its pivot so as to be swung freely thereon by a comparatively slight force and consisting of a laterally offset portion adapted to engage said filament and a substantially vertically depending leg portion adapted to be displaced from its vertical position when said laterally offset portion engages a filament properly located in said mount, means for raising said feeler toward said mount, and means operated by said depending leg portion of said feeler upon failure thereof to be displaced due to an improperly mounted filament or to the absence of a filament for indicating the presence of a defective mount in said holder.

4. In a device of the class described, a movable holder for incandescent lamp mounts comprising a filament and support wires engaging said filament, an inspection device disposed adjacent the path of movement of said holder comprising a feeler, mechanism for advancing said feeler toward said mount, said feeler being adapted to engage said filament and be displaced thereby when said filament is properly located on said mount, and an electrical circuit including switch means operated by said feeler upon failure thereof to be displaced due to an improperly mounted filament or to the absence of a filament for indicating the presence of the defective mount in said holder.

5. In a device of the class described, a movable holder for incandescent lamp mounts comprising a filament and support wires engaging said filament, an inspection device disposed adjacent the path of movement of said holder comprising a plurality of feelers having bifurcate end portions, mechanism for advancing said feelers toward said mount, said bifurcate end portions of each of said feelers being adapted to engage said filament on either side of a support wire and be displaced thereby when said filament is properly located in said mount, and means operated by any one of said feelers upon failure thereof to be displaced due to an improperly mounted filament or to the absence of a filament for indicating the presence of a defective mount in said holder.

6. The combination of a filament mounting machine comprising a plurality of heads for supporting mounts comprising a filament and support wires engaging said filament, with an in-

spection device disposed adjacent the path of movement of said heads and comprising a feeler, mechanism for advancing said feeler toward a mount in one of said mounting machine heads, said feeler being adapted to engage a filament in said mount and be displaced thereby when said filament is properly located on said mount, mount removing mechanism comprising holding means located adjacent said mount, means operated by said feeler upon failure thereof to be displaced due to an improperly mounted filament or to the absence of a filament for causing said mounting machine head to release the defective mount to the holding means of said mount removing mechanism, and means for actuating said mount removing mechanism to carry said defective mount away from said mounting machine head.

7. The combination of a filament mounting machine comprising a plurality of heads for supporting mounts comprising a filament and support wires engaging said filament, with an inspection device disposed adjacent the path of movement of said heads and comprising a feeler, mechanism for advancing said feeler toward a mount in one of said mounting machine heads, said feeler being adapted to engage a filament in said mount and be displaced thereby when said filament is properly located on said mount, mount removing mechanism comprising holding means located adjacent said mount, an electrical circuit including switch means operated by said feeler upon failure thereof to be displaced due to an improperly mounted filament or to the absence of a filament for causing said mounting machine head to release the defective mount to the holding means of said mount removing mechanism and for also causing said mount removing mechanism to carry said defective mount away from said mounting machine head.

8. The combination of a filament mounting machine comprising a plurality of heads for supporting mounts comprising a filament and support wires engaging said filament, with an inspection device disposed adjacent the path of movement of said heads and comprising a feeler, mechanism for advancing said feeler toward a mount in one of said mounting machine heads, said feeler being adapted to engage a filament in said mount and be displaced thereby when said filament is properly located on said mount, mount removing mechanism comprising holding means located adjacent said mount, an electrical circuit including two solenoids and a switch means operated by said feeler upon failure thereof to be displaced due to an improperly mounted filament or to the absence of a filament, one of said solenoids causing said mounting machine head to release the defective mount to the holding means of said mount removing mechanism and the other of said solenoids causing said mount removing mechanism to carry said defective mount away from said mounting machine head.

9. In a device of the type described, mechanism for removing defective mounts comprising a filament and supports therefor from supporting heads in a filament mounting machine comprising a sprocket, a chain carried thereby, a plurality of holders disposed at spaced intervals on said chain, means for advancing said sprocket toward one of said heads in said filament mounting machine to bring one of said holders to a position adjacent a mount in said head, inspection means for detecting the presence of a mount in said head having either an improperly mount-

ed filament or no filament at all, mechanism operated by said inspection means for causing said head to release a defective mount to the said holder adjacent thereto and for causing 5 said sprocket and chain to be indexed to carry said defective mount away from said filament mounting machine head.

10. In a device of the class described, a holder for an incandescent lamp mount comprising a filament and support wires engaging said filament, an inspection device disposed adjacent said holder and comprising a feeler, mechanism for advancing said feeler toward said mount, said feeler being adapted to engage said filament and 15 be displaced thereby when said filament is properly located on said mount, electrical switch means disposed adjacent said feeler, mechanism for advancing said switch means toward said feeler, said switch means being adapted to engage said feeler and be closed thereby upon failure of said feeler to be displaced due to an improperly mounted filament or to the absence of a filament, and an electrical circuit including said 20 switch means for indicating the presence of the 25 defective mount in the holder.

11. In a device of the class described, a mov-

able holder for incandescent lamp mounts comprising a filament and support wires engaging said filament, an inspection device disposed adjacent the path of movement of said holder comprising a pivotally mounted feeler balanced on its pivot so as to be swung freely thereon by a comparatively slight force and consisting of a laterally offset portion adapted to engage said filament and a substantially vertically depending leg portion adapted to be displaced from its vertical position when said laterally offset portion engages a filament properly located in said mount, means for raising said feeler toward said mount, electrical switch means disposed adjacent said feeler, mechanism for raising said switch means toward said depending leg portion of said feeler, said switch means being adapted to engage said depending leg portion of said feeler and be closed thereby upon failure thereof to be displaced due to an improperly mounted filament or to the absence of a filament, and an electrical circuit including said switch means for indicating the presence of the defective mount in the holder.
